DESIGN FOR A LAMP BASE

Ernest Bartlett, Collegeville, Pa., assignor to Arton Studios, Philadelphia, Pa., a copartnership consisting of Harry Greenberg and Harry Wilson

Application January 27, 1938, Serial No. 74,598

Term of patent 3½ years

To all whom it may concern:

Be it known that I, Ernest Bartlett, a citizen of the United States, residing at Collegeville, in the county of Montgomery and State of Pennsylvania, have invented a new, original, and ornamental Design for a Lamp Base, of which the following is a specification, reference being had to the accompanying drawing, forming part thereof.

looking in the direction of the arrows 1—1 in Figure 2 showing my new design.

I claim:

The ornamental design for a lamp base substantially as shown.

ERNEST BARTLETT.
